Primary Examiner — Susan Moon Lee(74) *Attorney, Agent, or Firm* — QuickPatents; Kevin Prince**CLAIM**

I claim the ornamental design for a spill proof pet food and water holding system, as shown and described.

DESCRIPTIONFIG. 1 is a side perspective view of a spill proof pet food and water holding system shown in a retracted position;
FIG. 2 is a front elevation view thereof;

FIG. 3 is a right side elevation view of the spill proof pet food and water holding system, the left side elevation view being a mirror image thereof;

FIG. 4 is a rear elevation view thereof;

FIG. 5 is a top plan view thereof;

FIG. 6 is a bottom view thereof;

FIG. 7 is a right side elevation view of the spill proof pet food and water holding system, shown in an extended position, the left side elevation view being a mirror image thereof; and,
FIG. 8 is a front elevation view thereof.**1 Claim, 4 Drawing Sheets**(56)
